[57] CLAIM

The ornamental design for a wall mounted jewelry case, as shown and described.

DESCRIPTION

FIG. 1 is a front elevational view of a wall-mounted jewelry case showing my new design;

FIG. 2 is a bottom plan view thereof;

FIG. 3 is a top plan view thereof;

FIG. 4 is a rear elevational view thereof;

FIG. 5 is a right side elevation view thereof, the left side being a mirror image thereof;

FIG. 6 is a front perspective view thereof, in a first alternate opened position, with the door and inside panel opened; and, FIG. 7 is a front perspective view thereof, in a second alternate opened position, with the door opened.

The cross-hatching shown in FIG. 6 indicates fabric which is understood to extend across the width of the surface.
